UNITED STATES PATENT OFFICE.

JOHN J. POWLICK, OF CLAIRTON, PENNSYLVANIA.

RAIL-JOINT.

1,342,065.

Specification of Letters Patent. Patented June 1, 1920.

Application filed December 12, 1919. Serial No. 344,475.

To all whom it may concern:

Be it known that I, JOHN J. POWLICK, a citizen of the United States, residing at Clairton, in the county of Allegheny and State of Pennsylvania, have invented certain new and useful Improvements in Rail-Joints, of which the following is a specification.

My invention consists of an improvement in rail joints, and particularly in means for fixedly connecting the meeting ends of rails, whereby to hold them in alinement with each other, without the use of connecting bolts or separable fish plates, or other similar devices.

The invention consists generally in a one-piece integral connecting bar composed of a base portion, oppositely located side embracing portions extending inwardly to the web and upwardly underneath the head of the rail, the end portions of the device being extended lengthwise beyond the side portions and constructed and adapted to operate in the manner more fully hereinafter set forth.

In the drawings,

Figure 1 is a general plan view showing the device as used with the meeting ends of two adjacent rails;

Fig. 2 is a view of the same in side elevation;

Fig. 3 is a view in end elevation, the rail being shown in section; and

Fig. 4 is a view of the device with the rails in position, in perspective.

In making my improved joint, which is preferably in the form of a single casting of steel or other suitable metal, I provide an under supporting base 2 which is extended upwardly at each side throughout its major middle portion, as indicated at 3-3, beyond which at each end, the base 2 is extended for a short distance, as indicated at 2^a, 2^a.

By this construction, the main upper flat seat portion of the base, upon which the flanges of the rails 4-4 are supported, is left plane throughout its entire width, and for a sufficient extent beyond the upwardly extending side members, for purposes hereinafter described.

The sides 3 are of ample cross section to provide sufficient strength for the maintenance of the joint under the usual strains of traffic, and extend inwardly over the flanges 4, providing an intervening receiving cavity

therefor, and abutting against the base portion of the rail web, and also extending upwardly in the manner of an ordinary fish plate into abutting engagement with the under sides of the head of the rail, as clearly shown in Fig. 3. By this means, the vertical supporting side members 5-5 are provided.

For the purpose of reinforcing these side members and of bracing them with relation to the laterally projecting portions 3, and also to provide ample abutting members for a jack or other pressure exerting tool, I provide at intervals the bracing ribs 6. As shown in Fig. 1, ribs 6 are preferably off-set from the corresponding ribs at the opposite side, and somewhat in conformity with the sloping end portions of the main housing portion of the joint member itself.

As shown, the side portions 3 and inner vertical wall members 5, above the upper plane of base 2, are sloped diagonally across the ends of the joint member, as indicated at 7, and 8 respectively. The sloping edge 7 extends almost entirely across each end of the side portions, practically co-extensive with the width of the rail flanges 4, the short sloping ends 8 being in a reverse direction, backwardly toward the opposite outer edges.

By this construction, the diagonal line of width of the receiving cavity of the joint is somewhat greater than the transverse width of the rail, and of the receiving cavity therefor, so that when either the rail or the joint are to be telescopingly connected, in bringing the parts together, one or the other may be thrust around out of alinement, whereby to present a somewhat wider opening for the rail than would be the case if the parts are brought together in the usual normal alinement. This construction facilitates the putting of the parts together in making the joint, and is of very considerable advantage in saving time and trouble.

As shown, the wider portion of the exposed narrow edge of the base 2 at each diagonally opposite side portion, is provided with a spike receiving space 9-9, so that the base 2 and also the flange 4 of each rail may be tightly secured down upon the usual supporting ties 10-10.

In using the rail joint as thus made, the outer end of the rail is slightly lifted from its loose position on the ties, the joint is introduced upon it in the diagonal manner above described until the end of the rail is

inserted in the receiving cavity, when it is then straightened around and thrust inwardly of the rail for the desired distance. The joint with the rail may be then lowered 5 upon the supporting ties and the end of the next adjacent rail may be introduced by its flange and web into the receiving cavity at the other end, straightened around, and then thrust into abutting contact with the end of 10 the already secured rail, when the joint is completed and may be spiked down in position.

The construction as thus made is comparatively simple in manufacture, capable of being 15 easily applied and used without the necessity of much skill, and will operate to perform its intended functions in a continuous satisfactory manner. It provides for sufficient movement of the rails, should any 20 movement be necessary, and avoids the necessity and objections of the usual bolts and nuts with their attendant loosening.

It may be made in any desired size, weight, dimensions, or otherwise varied in different 25 details by the skilled mechanic, but all such changes are to be considered as within the scope of the following claims.

What I claim is:

1. A one piece rail joint consisting of an 30 integral metal body portion having a main flat supporting base provided with a continuous plane bottom portion and a continuous plane upper rail supporting portion from end to end, upwardly enlarged side 35 portions extending above the edge portions of the base and inwardly and then upwardly thereof above its middle portion forming integral flanges and web embracing portions and an intervening space therebetween, 40 reinforcing bracing ribs thereon at opposite sides in non-registering positions, the ends of the upwardly extending side portions being slopingly arranged across the rail receiving space with respect to the 45 longitudinal center of the rail joint and terminating in short reversely sloped faces

at diagonally opposite corners, the terminals of all of said sloping faces being about equidistant from the several bracing ribs, the bottom portion of the rail joint extending 50 flush with the upwardly extending sides beyond said sloping faces and having at diagonally opposite positions an inwardly extending spike receiving recess adjacent the main sloping end portion of the joint, substantially as set forth.

2. In a rail joint, the combination with the adjacent ends of two meeting rails, of a one piece connecting member consisting of an integral metal body portion having 60 a main flat supporting base provided with a continuous plane bottom portion and a continuous plane upper rail supporting portion from end to end, upwardly enlarged side portions extending above the edge portions 65 of the base and inwardly and then upwardly therefrom above its middle portion forming integral flanges and web embracing portions engaging the flanges, web and head of the rails, reinforcing bracing ribs at opposite sides of said embracing portions in non-registering positions, the ends of the upwardly extending side portions being slopingly arranged across the side portions with respect to the longitudinal center of 70 the rail joint and terminating in short reversely sloped faces at diagonally opposite corners, the terminals of all of said sloping faces being about equidistant from the several bracing ribs, the bottom portion of the 75 rail joint extending flush with the upwardly extending sides beyond said sloping faces and having at diagonally opposite positions an inwardly extending spike receiving recess adjacent the main sloping end portion of the 80 joint whereby to provide for securing the base and rail by a spike to the supporting tie, substantially as set forth.

In testimony whereof I hereunto affix my signature.

JOHN J. POWLICK.
